PHILIP FRANCIS ODDIE, OF OSCHERSLEBEN, GERMANY.

DUPLEX PUMP.

SPECIFICATION forming part of Letters Patent No. 749,089, dated January 5, 1904.

Application filed March 9, 1903; Serial No. 146,983. (No model.)

To all whom it may concern:

Be it known that I, PHILIP FRANCIS ODDIE, civil engineer, a subject of the King of Great Britain and Ireland, residing at Oschersleben, near Magdeburg, in the German Empire, have made new and useful Improvements in Duplex Pumps, of which the following is the true specification.

This invention relates to duplex pumps, and more particularly to a new valve-gear for steam-cylinders of the same, the chief object being to provide such an arrangement that not only are the steam-inlet ports of the same length, but also that a double curvature of the same is avoided for the purpose of facilitating the casting of such steam-cylinders and the cleaning of the ports.

In many constructions of steam-cylinders the slide-faces are placed in the center between the two cylinders, and owing to this position of the slide-faces the steam-inlet ports cross each other, which not only complicates the casting, but also makes the steam-ports unequally long.

The casing of cylinders according to this invention is much simpler. The ports are all equally long and without curvature, so that they can be easily cleaned from sand, which hitherto has been very difficult to do.

In the accompanying drawings, Figure 1 is a plan of a duplex steam-cylinder with the valve-chest cover and valves removed for the purpose of clearly showing the steam-ports. Fig. 2 is a longitudinal section through one of the cylinders on line A B of Fig. 1. Fig. 3 is a cross-section showing the ports and the main and expansion valves. Fig. 4 is a plan of the main valve, and Fig. 5 a section through the latter on the line C D of Fig. 4.

a a' are the steam-cylinders, which are provided with slide-faces *b b'*, in which the main valves reciprocate. Each of these slide-faces is arranged directly over the center of its corresponding cylinder instead of between the two cylinders, as has been the general custom hitherto. In the slide-faces are the steam-inlet ports *c, c', c'',* and *c'''* and the exhaust-ports *d, d', d'',* and *d'''*. Located in a recessed portion 2 of the valve-chest and between the two slide-faces are guide-blocks *e e'* for the main valves, these blocks being

provided with oblique slots *ff'*. These blocks share in the reciprocating movement of the pistons, to which they are connected by means of valve-rod *k* and arms *h*, which arms are attached to the piston-rods. By reason of the arrangement of the slide-faces immediately over the center of each cylinder the ports are not only of the same length, but also lead to the ends of the cylinder without double curvature. The main valves *l l'* are provided, respectively, with laterally-projecting arms *m m* and *m' m'*, which overlap in the center, as shown in Figs. 4 and 5. The ends of the arms *m' m'* are connected by the guide-piece *n*, and the ends of the arms *m m* are connected by the guide-piece *n'*. These guide-pieces engage in the oblique slots *ff'* of the guide-blocks *e e'*, so that when one piston and its guide-block are moving the driving of the corresponding valve is necessarily effected laterally relatively to the direction of the movement of the piston. The outer ends of the valves are made heavy, so as to balance the weight of the projecting arms and guide-pieces. The valve *l* is provided with passages *s* and *u* and a long slot *t*, and the valve *l'* is similarly provided with passages *s'* and *u'* and a long slot *t'*. Projecting upwardly from the guide-piece *n* is a projection *p*, having a circular slot in its upper end for the purpose of guiding the rod 3, on which one of the expansion-valves is mounted. This rod 3 is provided with two ears or nuts 4 4, located one on each side of the projection *p*. Each of the rods 3 carries two blocks 5 and 6, which are screw-threaded on said rod, these screw-threads being right and left handed, respectively, so that the turning of said rod will cause the parts 5 and 6 to move backward and forward. The parts 5 and 6 are prevented from movement by reason of their shape, as shown in Fig. 2, being provided with corners engaging a recess 7 in the valve *l*. The expansion-valve 95 over the valve *l'* is similar in construction and needs no further description. The rod 3, which carries one of the expansion-valves, has its outer end squared, as shown at 8 in the right-hand portion of Fig. 3. This squared portion engages in a square socket 9 of a casing 10, to which is attached the hand-

wheel 11 for moving the same. By turning the hand-wheel 11 it is obvious that the expansion-valve will be moved backward or forward on the main valve, thus opening or closing the passages in the corresponding main valve to a greater or less extent.

In operation the steam is admitted through the port *q*, passes into the valve-chest through the openings in the main valves and then through the inlet-ports into the cylinders, then out through the outlet-ports in the valve-seats and passages in the valves, and escapes through the port *r*.

Having now particularly described and ascertained the nature of this said invention and in what manner the same is to be performed, I declare that what I claim is—

1. A pump comprising a cylinder, a valve-chest over said cylinder, a main valve mounted in said valve-chest and adapted to slide upon its seat transversely across said cylinder, an adjustable expansion-valve mounted above said main valve, and means for imparting to said valves a movement transverse to said cylinder.

2. A pump comprising a cylinder, a valve-chest over said cylinder, a main valve mounted in said valve-chest, a valve-seat disposed transversely across said cylinder over which said main valve moves, a set of admission and exhaust ports in said valve-seat, the admission-ports being oppositely disposed in relation to the exhaust-ports and leading in a direct course to the cylinder below, an adjustable expansion-valve located above the main valve, and means for moving said valves across said valve-seat.

3. A duplex pump comprising parallel cylinders, a valve-chest located above said cylinders, main valves within said valve-chest adapted to move across the valve-seats transversely of said cylinders, admission-ports of equal length leading from said valve-seats to said cylinders, exhaust-ports located directly opposite to said admission-ports, inlet and outlet passages in said valves and adjustable expansion-valves located above said main valves, and means for actuating all of said valves.

4. A duplex pump comprising the cylinders, valve-chests upon said cylinders, valve-seats located centrally above said cylinders, valve-seats in said valve-chests, admission and exhaust ports arranged alternately and opposite one another, the admission - ports leading from said valve-seats directly to the cylinder, main valves adapted to move over said valve-seats transversely to the cylinder, admission-ports formed in said main valves adapted to register with the admission-ports in said valve - seats, an expansion - valve mounted upon said main valve and adapted to control said admission-ports, an exhaust-passage in each of said main valves, adapted to connect the admission and exhaust ports at intervals, and means for actuating said valves.

5. A duplex pump comprising the cylinders, valve-chests upon said cylinders, valve-seats located centrally above said cylinders, valve-seats in said valve-chests, admission and exhaust ports arranged alternately and opposite one another, the admission - ports leading from said valve-seats directly to the cylinder, main valves adapted to move over said valve-seats transversely to the cylinders, admission-ports formed in said main valves adapted to register with the admission-ports in said valve - seats, an expansion - valve mounted upon said main valve and adapted to control said admission-ports, an exhaust-passage in each of said main valves, adapted to connect the admission and exhaust ports at intervals, laterally-extending arms carried by said main valves, and means connected to said arms for imparting a transverse movement to said valves relatively to the cylinders.

6. A duplex pump comprising the cylinders, valve-chests upon said cylinders, valve-seats located centrally above said cylinders, valve-seats in said valve-chests, admission and exhaust ports arranged alternately and opposite one another, the admission - ports leading from said valve-seats directly to the cylinder, main valves adapted to move over said valve-seats transversely to the cylinders, admission-ports formed in said main valves adapted to register with the admission-ports in said valve - seats, an expansion - valve mounted upon said main valve and adapted to control said admission-ports, an exhaust-passage in each of said main valves, adapted to connect the admission and exhaust ports at intervals, laterally-extending arms carried by said main valves, and means connected to said arms for imparting a transverse movement to said valves relatively to the cylinders.

7. A duplex pump comprising the cylinders, valve-chests upon said cylinders, valve-seats located centrally above said cylinders, valve-seats in said valve-chests, admission and exhaust ports arranged alternately and opposite one another, the admission - ports leading from said valve-seats directly to the cylinder, main valves adapted to move over said valve-seats transversely to the cylinders, admission-ports formed in said main valves adapted to register with the admission-ports in said valve - seats, an expansion - valve mounted upon said main valve and adapted to control said admission-ports, an exhaust-passage in each of said main valves, adapted to connect the admission and exhaust ports at intervals, laterally-extending arms carried by said main valves, valve-stems carried by said expansion-valves, and means connected to said arms and said valve-stems for imparting motion to said valves.

8. A duplex pump comprising the cylinders, valve-chests upon said cylinders, valve-seats located centrally above said cylinders,

valve-seats in said valve-chests, admission and exhaust ports arranged alternately and opposite one another, the admission-ports leading from said valve-seats directly to the cylinder, main valves adapted to move over said valve-seats transversely to the cylinders, admission-ports formed in said main valves adapted to register with the admission-ports in said valve-seats, an expansion-valve 5 mounted upon said main valve and adapted to control said admission-ports, an exhaust-passage in each of said main valves, adapted to connect the admission and exhaust ports at intervals, laterally-extending arms carried 10 by said main valves, valve-stems carried by 15

said expansion-valves, guide-blocks provided with inclined grooves in which rest projections upon said arms, upwardly-extending projections carried by said arms, and adapted to engage the valve-stems of said expansion-valves, and means for imparting a reciprocatory motion to said blocks. 20

In testimony whereof I have affixed my signature in presence of two subscribing witnesses.

PHILIP FRANCIS ODDIE.
